Specification for Design.

Patented Oct. 7, 1919.

Application filed November 21, 1917. Serial No. 203,270. Term of patent 14 years.

To all whom it may concern:

Be it known that I, Roy W. Hill, a citizen of the United States, residing at Chicago, county of Cook, and State of Illinois, have invented a new, original, and ornamental Design for an Automobile Signal-Lamp, of which the following is a specification, reference being had to the accompanying drawings, forming a part thereof.

Figure 1 is a front elevation or face view of an automobile signal lamp, showing my new design; and

Copies of this patent may be obtained for five cents each, by addressing the "Commissioner of Patents, Washington, D. C."

Fig. 2 is a top plan view of the same.
I claim:

The ornamental design for an automobile signal lamp, substantially as shown.

In testimony whereof I have hereunto signed my name in the presence of two subscribing witnesses.

ROY W. HILL.
